(57) **CLAIM**

The ornamental design for a floor lamp base, substantially as shown and described.

DESCRIPTION

FIG. 1 is a perspective view of a floor lamp base showing my new design in context;

FIG. 2 is a side plan view thereof;

FIG. 3 is a rear view thereof;

FIG. 4 is a front view thereof;

FIG. 5 is a top view thereof;

FIG. 6 is a bottom view thereof;

FIG. 7 is a perspective view showing my new design;

FIG. 8 is a side view of the base shown in FIG. 7;

FIG. 9 is a rear view thereof; and,

FIG. 10 is a front view thereof.

Features shown in broken lines in FIGS. 1-6 are shown for environment only and do not form a part of the claimed design.

In FIGS. 7-10, the stand is shown broken away from a lighting unit for convenience of illustration.
